UNITED STATES PATENT OFFICE.

LOUIS MEYLACH, OF BROOKLYN, NEW YORK.

EDGE-SLITTING MACHINE.

Application filed December 8, 1926. Serial No. 153,396.

This invention relates to edge slitting machines and has for its object to provide a machine of the class specified, of simple construction, easy of manipulation and swift 5 and accurate in operation.

To these ends and others which will appear later herein my improvements comprise features illustrated in their preferred embodiment in the drawings accompanying 10 this specification, wherein:

Figure 1 is an end elevation of my improved machine. Fig. 2 is a rear elevation corresponding therewith. Fig. 3 is a plan of the major portion of what is shown above 15 the table top in Figs. 1 and 2. Fig. 4 is an elevation partly in section on line 4-4 of Fig. 3 and Fig. 5 is a similar section on line 5-5 of Fig. 3. Fig. 6 is a fragmentary section showing parts adjacent to and overlapping the left portion of Fig. 5. The scale of Figs. 1 and 2 is the same, and the scale of the other figures is about four times that of Figures 1 and 2.

While my improvements are adapted for 25 employment in a wide field, they are herein illustrated as particularly designed for slitting the edges of felt hats, such for instance as simply indicated at 3 in Fig. 5.

Directing attention now more particularly 30 to the drawings my improvements may be conveniently mounted on opposite sides of a horizontal plate 2, preferably supported on short legs as 6, and which legs may rest on a bench as 7 to raise the device a suitable 35 distance from the floor for convenient operation.

The cutting or slitting tool comprises a 40 rotary circular cutting disc 8 having its edge sharpened. Said disc is removably secured to the upper end of vertical spindle 9 rotatably mounted in bearings in block 10 depending from table or plate 2. To the lower 45 end of spindle 9 is fixed pulley 11. Spindle 9 comprises upper and lower portions, the lower portion being constrained against vertical movement and the upper portion being vertically adjustable so that cutter may be set at varying distances from the top face 50 of table 2 to accommodate various thicknesses of brims 3. Rotary motion is transmitted from the lower to the upper portion of said spindle through the flattened spindle elements shown at 12. For adjusting the upper portion of said spindle vertically, 55 grooved collar 13 is fixed to said spindle portion and yoked lever 14 pivoted at 15 in an

ear of block 10 has opposite pins as 16 in engagement with the rim groove in said collar. The upper end of lever 14 projects upwardly to above table 2 into convenient 60 accessibility and terminates in ear 17 through which is threaded adjusting screw 18, whose left hand end, Fig. 6, is revolvably mounted in bracket 19, reaching rearwardly from 65 table 2.

For rotating the hat brim 3 and presenting its edge to the action of cutter 8 a pair of feed rolls 20, 21 are provided. These are arranged one above the other at the left of cutter 8, Fig. 3 and their parallel axes are 70 angularly disposed, the inreaching ends of the rolls pointing toward the center of the hat. Lower roll 21 has its upper edge approximately in the plane of the table top and upper roll 20 is spring urged toward 75 said lower roll, so that said rolls are efficient for gripping and feeding forwardly toward the left, a hat brim fed therebetween. The shaft 22 of roll 21 has bearings projecting downwardly from table 2 and upper roll 80 shaft 23 has its bearing in vertically slidable block 24 in housing 25 urged downwardly by adjustable spring 26. Shafts 22, 23 are geared together by gears 27, 28 respectively and bevel gear 29 fixed to shaft 22 meshes 85 with and is driven by bevel gear 30. Said gear 30 is fixed to worm gear 31 and they together turn on stud 32 depending from table 2.

Adjacent worm gear 31 is bracket 33, fixed 90 to the lower face of table 2 and therein is revolvably mounted shaft 34 to which is fixed worm 35 engaging and driving said worm gear. Also to shaft 34 is fixed pulley 36. Pulleys 11 and 36 are driven by the usual 95 belts from suitable pulleys on shaft 37 of motor 38.

For holding hat brim 3 snugly against table 2 as the brim is fed forwardly to the left, Fig. 3, in engagement with cutter 8, 100 presser foot 39 is employed. Said presser foot is preferably a portion of a flat annular ring conforming to and overlying the periphery of the cutter, thereby performing the double function of a cutter guard and 105 presser foot. Said presser foot is fixed to the lower end of vertical stem 40 slidably mounted in bracket 41 upstanding from table 2 and adjustable thereon to accommodate different diameters of cutters.

Fixed to said stem 40 is block 42 which 110 engages the face of bracket 41 to prevent

rotation of stem 40 while permitting vertical movement thereof. Between the upper face of block 42 and adjusting screw 43 is spring 44 for urging presser foot 39 downwardly. 5 For limiting the downward movement of presser foot 39 screw 45 is threaded in block 42 and abuts against lower ear 46 of bracket 41.

For guiding the hat body 3^a so that the 10 edge of brim 3 will be properly presented to cutter 8 outside roll 47 is mounted for free rotation in the right hand end of arm 48, Fig. 5, and is adjustable therein, to accommodate different widths of brim. For cooperation with roll 47, inside roll 49 is pivotally mounted in block 50 slidably mounted below table 2. Stud 51 on which said roll 49 turns, projects upwardly through slot 52 in table 2. Said block 50 is spring urged 15 to the left and may be withdrawn to the right to admit a hat between rolls 47, 49, by means of pull chain 53, one end of which is fixed to said block and the other end to foot treadle 54, Fig. 1, the chain passing 20 over pulley 55 fixed to the under part of 25 table 2.

I claim:

1. In a machine of the character specified 30 the combination of a revoluble cutter, means for rotating said cutter, means for adjusting said cutter axially, a roll for spacing for depth of cut an article to be slitted, relatively to said cutter, means for adjusting said roll relatively to said cutter, a second 35 roll, spring urged and slidably mounted, for

40 maintaining said article in operative engagement with the first mentioned roll, means for withdrawing said second roll from coaction with said first mentioned roll, means for feeding an article to be slitted to engagement with said cutter comprising a pair of feed rolls, means for rotating said rolls, spring means for urging one of said rolls toward the other thereof and means for adjusting said spring means. 45

2. In a machine of the character specified, the combination of a revoluble cutter, means for rotating said cutter, means for adjusting said cutter axially, a roll for spacing for 50 depth of cut an article to be slitted, relatively to said cutter, means for adjusting said roll relatively to said cutter, a second roll, spring urged and slidably mounted, for maintaining said article in operative engagement with the first mentioned roll, means for feeding an article to be slitted to engagement with 55 said cutter comprising a pair of feed rolls, means for rotating said rolls, spring means for urging one of said rolls toward the other thereof, a presser foot, spring urged, for holding down an article to be slitted, means for adjusting said spring means, said presser foot being curved for overlying a portion of the cutting edge of said cutter and adjustable means for limiting the downward movement of said presser foot. 60

In witness whereof, I hereby affix my signature this 6th day of December, 1926.

LOUIS MEYLACH.
